WATERPROOF SPAT

Martin Glowka, New York, N. Y.

Application January 11, 1938, Serial No. 184,364

6 Claims. (Cl. 36—2)

My invention relates to waterproof spats and has particular reference to spats worn over ordinary shoes for the protection of a wearer's ankles.

5 My invention has for its object to provide spats which can be fitted tightly over ordinary shoes so as to prevent any excess of water or dirt from penetrating into the space between the material of the spats and the shoes, and to provide a still greater degree of protection than was disclosed 10 in my Patent No. 2,099,476 of Nov. 16, 1937, and my patent application Serial No. 178,459, filed Dec. 7, 1937. For this purpose I provide a plurality of straps extending across the sole of a shoe between the edges of the spats. I also provide reinforced edges for the spats adapted to fit 15 snugly against the sides of the shoe. I also provide the straps with buckles or buttons for drawing them tightly against the spats and for 20 stretching the edges of the spats lengthwise so as to cause them to fit tightly against the edges of the soles of the shoes.

Another object of my invention is to provide the spats with edges fitting against the upper 25 sides of the edges of the soles of the shoes, the edges of the spats having relatively thin flexible extensions or flaps covering the edges of the soles.

Another object of my invention is to provide the upper portions of the spats with slits which 30 can be closed by ordinary slide fasteners, the latter being covered from inside and outside with suitable flexible flaps, the outer flaps having additional snap fasteners for removably holding them against the spats.

35 Another object of my invention is to provide spats with a plurality of detachable ornamental straps extending across the front sides of the spats, the straps being of various colors which can be selected so as to match other garments of 40 a wearer of the spats.

Still another object of my invention is to provide spats having bellows-shaped collapsible middle portions, partly for ornamental purpose, partly to enable the spats to be stretched to a 45 greater length when so needed.

My invention is more fully described in the accompanying specification and drawing in which—

Fig. 1 is a side view of my spat on a man's shoe.

50 Fig. 2 is a bottom view of the same.

Fig. 3 is a side view of another form of my spat on a woman's shoe.

Fig. 4 is a bottom view of the same.

Fig. 5 is a side view of a modified spat.

55 Fig. 6 is a bottom view of the same.

Fig. 7 is a fractional detail view of the edge of my spat in section.

Fig. 8 is a side view of a modified form of my spat.

Fig. 9 is a view of another modification. 5

Fig. 10 is a bottom view of the same.

Fig. 11 is a detail view of a strap on the toe portion of a shoe.

Fig. 12 is a side view of still another modification. 10

Fig. 13 is a fractional detail view of straps.

Fig. 14 is a fractional sectional detail view of the edge of the spat.

Fig. 15 is a similar view of a modification.

Fig. 16 is a fractional side view of a strap. 15

Fig. 17 is a side view of a modified spat.

My spat consists of an enclosure 1 made of a flexible, preferably waterproof material, such as rubberized cloth, etc. It covers the ankle portion of a wearer's foot and the upper portion of a 20 shoe down to its sole 2 and heel 3. The side of the enclosure 1 has a slit which can be closed by an ordinary slide fastener 4 preferably of the Zipper type. The heel portion of the spat enclosure has an elastic band 5 tightly enclosing 25 the heel 3. The lower edges of the enclosure 1 are reinforced by an elastic bead 6 and are connected by a sole portion 7 of the enclosure extending to the band 5. Additional resilient or 30 elastic straps 8 are fitted over the sole 7 at the instep portion of the shoe. This modification is shown in Figs. 1 and 2. Figs 3 and 4 represent another modification in which detachable straps 9 and 10 are provided under the shank portion of the shoe. The upper portion of the enclosure 11 35 has a closing flap 12 with a snap fastener 13.

Figs. 5 and 6 illustrate a spat in which the enclosure 14 is opened at the bottom and provided with a toe closure 15 curved as shown and bent inwardly as shown in Fig. 5 in dotted lines. 40 Straps 16 and 17 join the edges at the instep, the strap 16 being curved as shown in direction opposite to the curvature of the toe closure 15, the strap 16 and the closure 15 being adapted to stretch the edges of the enclosure 14 over the 45 edges of the shoe sole 2, the edges being drawn together in parallel relation to each other as shown in Fig. 6. The bead 6 is shown in detail in Fig. 7.

A modified spat is shown in Fig. 8 of a type 50 resembling a Russian boot. The enclosure 18 has a number of flexible folds or corrugations 19 in the middle which can be straightened out to increase the length of the spat.

Another modification is shown in Figs. 9, 10, 55

and 11. The enclosure 20 has straps 21 and 22 extending from the lower edges and crossing the sole 2 of the shoe, the free ends of the straps being bent over the upper portion of the toe portion of the enclosure and detachably attached by snap fasteners 23. The straps are attached alternately to the enclosure 20 as shown, the attached ends being of an enlarged shape so as to draw wider portions of the enclosure against the sole 2 of the shoe.

A modification shown in Fig. 12 has a slit in the upper portion which can be closed by a slide fastener or Zipper 24. The Zipper is protected inside by a flap 25 and on the outside by a flap 26 attached at one side to the enclosure and having snap fasteners 27 at the other side.

The straps may fully encircle the toe portion of the enclosure as shown in Fig. 13 where a strap 28 has a buckle 29 for drawing the strap tightly against the shoe.

The enclosure 30, as shown in Fig. 14, may have a relatively heavy edge 31 fitting into the space between the upper side of the edge of the sole 2 and the toe portion 32 of a shoe. A relatively thin flap 33 extends down from the enclosure and covers the edge of the sole 2. A strap 34 has an undercut 35 opposite the edge of the sole 2 in order to enable the strap to be bent at a sharp angle as shown. The strap may be slidably fitted in strips 36 attached at their ends to the enclosure 37 as shown in Figs. 15 and 16.

The enclosure 38, Fig. 17, may be provided with detachable ornamental straps 39 with snap fasteners 40 at both ends. These straps may be made of different colors to match the wearer's dress, this arrangement being especially suitable for women's spats.

I claim as my invention:

1. A waterproof spat comprising a flexible enclosure for the upper portion of a shoe, a bridge member connecting the edges of the enclosure under the toe portion of the shoe forming a pocket for the latter, a plurality of elastic straps connecting the edges of the enclosure under the shank portion of the shoe, the front strap having forward curved ends adapted to pull the edges of the enclosure rearward thereby drawing the edges tightly over the edges of the sole of the shoe.

50 2. A waterproof spat comprising a flexible enclosure for the upper portion of a shoe, a bridge

member connecting the edges of the enclosure under the toe portion of the shoe forming a pocket for the latter, a plurality of elastic straps connecting the edges of the enclosure under the shank portion of the shoe, the front strap having forward curved ends adapted to pull the edges of the enclosure rearward thereby drawing the edges tightly over the edges of the sole of the shoe, and reinforcing beads extending along the lower edges of the enclosure between the toe bridge and strap.

3. A waterproof spat comprising a flexible enclosure for the upper portion of a shoe, a bridge member connecting the edges of the enclosure under the toe portion of the shoe forming a pocket for the latter, a plurality of elastic straps connecting the edges of the enclosure under the shank portion of the shoe, the front strap having forward curved ends adapted to pull the edges of the enclosure rearward thereby drawing the edges tightly over the edges of the sole of the shoe, and reinforcing beads extending along the lower edges of the enclosure between the toe bridge and strap.

4. A waterproof spat comprising a flexible enclosure for the upper portion of the shoe, a plurality of straps extending over the sole of the shoe and over the toe portion of the enclosure and adapted to draw the enclosure tightly against the shoe, and means to slidably guide the straps on the enclosure.

5. A waterproof spat comprising a flexible enclosure for the upper portion of a shoe down to its sole, straps extending over the sole between the edges of the enclosure, and means to slidably support the straps on the enclosure, the straps being undercut at the points of flexure over the edges of the sole.

6. A waterproof spat comprising a flexible enclosure for the upper portion of a shoe down to its sole, the lower edges of the enclosure being adapted to abut the upper sides of the edges of the sole, relatively thin flaps extending from the enclosure over the edges of the sole, and straps adapted to draw the enclosure tightly against the shoe.

50 MARTIN GLOWKA.
